UNITED STATES PATENT OFFICE.

JACOB D. WELLIVER AND WILLARD G. HARRINGTON, OF SCRANTON, PENNSYLVANIA.

DOOR TRACK AND HANGER.

No. 880,258.

Specification of Letters Patent.

Patented Feb. 25, 1908.

Application filed August 26, 1907. Serial No. 390,238.

To all whom it may concern:

Be it known that we, JACOB D. WELLIVER and WILLARD G. HARRINGTON, citizens of the United States, residing at Scranton, in the county of Lackawanna and State of Pennsylvania, have invented certain new and useful Improvements in Door Tracks and Hangers, of which the following is a specification.

10 Our invention comprises improvements in tracks and hangers especially adapted for freight car doors, but suitable, also, for other structures.

The details and advantages of our improvements will be clear from the following specification, taken in connection with the accompanying drawing in which,

Figure 1 is a front view of the track and hanger, showing also the upper end of the door; Fig. 2 is a rear view of the track; Fig. 3 is a vertical section through the track and hanger on a larger scale than the other figures of the drawing; Fig. 4 is a front view of the hanger; Fig. 5 is a plan view of the ball retainer, and Fig. 6 is a section through the track and hanger on the line 6—6 of Fig. 3.

Referring to the drawing A indicates the track, B indicates the door hanger, C indicates a ball retainer or spacer which fits loosely between the opposing parts of the track and hanger and 1 and 2 indicate metal balls arranged in suitable openings in the end portions of the ball retainer or spacer.

The hanger B consists of a metal bar, 35 equal in length to the width of the door D and having a flat portion b, secured to the upper end of the door, at the rear side of the latter, and a part b' projecting outwardly above the door and of substantially semi-cylindrical shape in cross section, forming a race-way on the hanger. The track A comprises a metal bar, approximately twice as long as the hanger, but of course the length of the track will depend upon the width of 45 the doorway and the lap of the door over the sides of the doorway. The track is adapted to be secured in horizontal position above the doorway by suitable means such as the bolts 3 passing through a series of perforations 4 near the upper edge of the track. The track has two reverse bends 5 and 6, extending longitudinally thereof, which give the track an ogee shape in cross section, as shown in Fig. 3. Thus when the track is in 55 position upon a car body or other structure,

E, the central part a of the bar, between the outward bend 5 and inward bend 6, inclines away from the structure to which the track is attached, and forms a shield to protect the parts beneath it from the weather and from 60 cinders, etc. The inwardly turned portion a' of the track, below the bend 6, is semi-cylindrical in cross section, and forms a race-way for the balls 1 and 2, which are arranged between the track and hanger, within the 65 race-ways, as shown. Where the race-way portion a' of the track joins the body portion, the upper edge 7 of the race-way is faced off horizontally in the same plane as the edge 8, and similarly the edge 9 of the 70 race-way b' is faced off parallel with the edge 10, so that the edges of the walls of the two race-ways are opposed, but separated by the balls 1 and 2, when the hanger is in position. Within the recesses e and f, between the 75 opposing edges of the race-way walls, is arranged the ball retainer or spacer C. This ball retainer as shown in Fig. 5 consists of a flat strip of metal, approximately one half as long as the door hanger, and having near 80 its ends circular openings 11 and 12 of slightly greater diameter than the diameter of the balls 1 and 2, which fit loosely within the openings.

Stops 13 and 14 (Fig. 6) are provided at 85 the ends of the race-way b' of the hanger, these stops being arranged to engage the upper halves of the balls, to prevent the latter from working out under the hanger, and the end portions 15 and 16 of the race-way a' of 90 the track are slightly elevated, as shown in Figs. 2 and 6, so as to give support to one side or other of the door in its open or closed position.

When the door is at one end of the track, 95 as shown in Fig. 1, which may be taken as the closed position of the door, one of the balls will be near the center of the hanger and the other ball will be at one end of the hanger, while the opposite end of the hanger will rest upon the raised part of the track, as shown in dotted lines in Fig. 1 and in full lines in Fig. 6. When the door is moved to the left in Fig. 1 the hanger will roll along on the balls and in the extreme left hand position of the door the ball 1 will be about at the center of the hanger and the ball 2 at the right hand end of the hanger while the left hand end of the hanger will be supported by the adjacent raised portion 15 of the track.

The ball retainer or spacer keeps the balls a certain distance apart, equal to a little less than one half the width of the door. When the door is moved away from one end of the track it rides freely on the balls until it approaches the opposite end of the track, when one end of the hanger will ride onto the raised portion of the track, and this engagement of the track and hanger will frictionally retard the movement of the door and also hold the door frictionally in position. The track may be closed at its ends if desired, to prevent the entrance of snow, rain, cinders, etc.

What we claim is

- 15 1. A track comprising a metal bar having a part near one edge adapted for attachment to a car or other structure, and having its central portion inclined outwardly to form a shield and its lower portion turned inwardly and curved to form a raceway, said raceway having parallel upper edges, in combination with a hanger comprising a bar having a flat portion adapted for attachment to the upper end of a door, and having its upper portion turned outwardly and curved to form a raceway, said latter raceway having parallel lower edges opposed to the edges of the track raceway, and having stops at its ends, a ball retainer comprising a flat plate arranged 20 between the raceways of the track and hanger, and supported upon the edges of the track raceway, said plate having openings therein spaced apart a distance equal to approximately one half the width of the door, and balls within said 25 openings between said stops.
- 20 25 30

and balls within said openings between said stops.

2. A track comprising a metal bar having a part near one edge adapted for attachment to a car or other structure, and having its central portion inclined outwardly to form a shield and its lower portion turned inwardly and curved to form a raceway, said raceway having parallel upper edges the ends of which extend slightly above their intermediate portions, in combination with a hanger comprising a bar having a flat portion adapted for attachment to the upper end of a door, and having its upper portion turned outwardly and curved to form a raceway, said raceway having parallel lower edges opposed to the edges of the track raceway, and having stops at its ends, a ball retainer comprising a flat plate, shorter than the hanger, arranged between the raceways of the track and hanger, and supported upon the edges of the track raceway, said plate having openings therein spaced apart a distance equal to approximately one half the width of the door, and balls within said openings between said stops.

In testimony whereof we affix our signatures, in presence of two witnesses.

JACOB D. WELLIVER.

WILLARD G. HARRINGTON
